PRESSURE REGULATOR FOR PRESSURE PRESSES

George W. Elsey, Dayton, Ohio, assignor to Delco Products Corporation, Dayton, Ohio, a corporation of Delaware

Application July 30, 1932. Serial No. 626,862

8 Claims. (Cl. 29—86)

This invention relates to improvements in pressing machines and particularly in control devices for such pressing machines.

It is among the objects of the present invention 5 to provide a control device for a pressing machine which, if the pressing machine does not exert a proper pressure upon the work-piece, will stop the operation of the machine and thereby avoid an improper operation upon the work-piece.

Further objects and advantages of the present invention will be apparent from the following description, reference being had to the accompanying drawing wherein a preferred embodiment of one form of the present invention is clearly shown.

In the drawing, on which the device is shown diagrammatically, the numeral 20 designates the main body of the machine having a recess 21 20 providing a cylinder for the reception of the piston 22. This piston forms the base for supporting the work-piece. In this instance the work-piece consists of an arm 23 having an opening 24 therein which is adapted to receive the knurled end 25 of a shaft 26. This shaft, when pressed into the opening 24 of the arm, will be rigidly secured to said arm.

In order to establish a substantially leak-proof connection between the wall of the recess 21 and the piston 22, a counter-bored recess 27 in the outer end of recess 21 forms a packing chamber containing the packing element 28 held in proper sealing position by the gland 29. A bracket 30 extends from the main body of the machine 20, 35 this bracket having a head portion providing a cylinder 31 which communicates with another cylinder of reduced diameter designated by the numeral 32. A duct or passage 33 connects the recess 21 with the cylinder 32. Within the cylinder 32 a piston 34 is reciprocably supported, said piston having an enlarged head portion 35 slidably within the cylinder portion 31. To the piston 35 there is attached the stop-member or 40 detent 36, which has a head portion 37 slidably engaging abutment block portion 38 of the bracket 30. A spring 39 interposed between the piston portion 35 and a cylinder head 40 threaded into the open end of cylinder portion 31, normally, 45 yieldably urges the said piston portion against the shoulder provided between the two cylinder portions 31 and 32.

When in normal position, the stop member or 50 detent head portion 37 is in the path of movement of a ram 50, which is adapted to exert pressure upon the work-piece 26. This ram 50 may

be moved by any suitable source of power, in the present instance it is shown as being moved by hydraulic power, ram 50 forming a portion of a piston 51 within the cylinder 52. Hydraulic pressure for moving the ram 50 upon its pressure exerting stroke is provided through the pipe 53, the application of said fluid pressure through said pipe being controlled by a manually operable valve 54. The source of fluid pressure supply is received through the pipe 55 connected with the control valve 54. Pipe 56 connected with the control valve 54 leads into the side of the cylinder 52. The fluid pressure from pipe 56 directed into the cylinder 52 is adapted to return the ram 50 to normal inoperative position, as shown in the drawing.

It will be seen that the portion 60 of the ram 50, which is adapted to engage with the stop-member or detent 37, is normally spaced therefrom so that said detent will not engage the ram until it has moved through an initial portion of its range of movement. During this initial portion of its range of movement, the ram will have engaged the work-piece 26 and will have pressed or forced said work-piece portion 26 partially into the opening 24 of the arm 23 to which shaft 26 is to be attached. The passage or pipe 65 with its ball check-valve 66 is provided to supply fluid to the recess chamber 21 if the fluid supply therein has been depleted for any reason such as 85 leaks or the like.

It will be seen that the fluid column in the duct or passage 33 maintains the base piston 22 in a position so that a space or chamber 69 is normally provided between the bottom surface of said piston 22 and the bottom of the recess 21. Thus it may be seen that the piston 22 is yieldably supported within its cylinder 21. The spring 39 is of sufficient tension so that it will normally maintain the piston portion 35 in the position shown in the drawing, or in the position in which the fluid column within the passage 33 and within the chamber 69 will maintain piston 22 in this suspended position.

When the operator depresses the pedal 67 to 100 permit fluid pressure to be transmitted from the pipe 55 through pipe 53 into the cylinder 52 against the top of the piston 51, the ram 50 will be moved downwardly in the direction of the arrow 68, the ram engaging the work-piece portion 26 and pushing it or pressing it into the opening 24. If the fit between the shaft 26 and the opening 24 in the arm 23 is not sufficiently tight, or more specifically, if the fit of shaft 26 in the opening 24 is too loose, then the pressure required 110

to push the shaft in said opening will not force the piston 22 downwardly into its cylinder 21 against the effect of the spring 39 hydraulically to maintain said piston 22 in a normal position, consequently the stop-member or detent 37 will remain in its normal position as shown in the drawing, thereby being engaged by the ram 50 when it has moved through its initial portion of movement. This will eliminate the completion of the insertion of shaft 26 into the opening 24, for, as has been said heretofore, the fit between these two parts in this instance is too loose. On the other hand, if the insertion of shaft 26 into the opening 24 provides sufficient resistance to the movement of the ram 50 in the direction of the arrow 68, that is, if the fit between shaft 26 and opening 24 is sufficiently tight to produce a good assembled device, then piston 22 will be moved downwardly in its cylinder 21 against the effect of spring 39, and thus the fluid column in channel 33 and chamber 69 will move piston 34 and its portion 35 against the effect of spring 39, resulting in a movement of the detent 36 to retract its head portion 37 from the path of movement of the ram. This permits continuation of the ram movement 50 in a direction of the arrow 68 to provide for the complete insertion of the knurled portion 25 of shaft 26 into the opening 24 or arm 23.

From the foregoing description it may be seen that applicant has provided a control mechanism for a pressing machine which will not permit a complete cycle of operation of the machine if the work-pieces upon which the machine is operating are not properly being assembled. More specifically, if the work-pieces being assembled by the machine are not of a proper fit, the control device will remain in its normal position so that the machine can operate through only a portion of its cycle, while on the other hand, if the work-pieces properly fit to provide a suitable assembled piece, then the control device will operate to permit a complete cycle of operation of the press.

While the form of embodiment of the present invention as herein disclosed, constitutes a preferred form, it is to be understood that other forms might be adopted, all coming within the scope of the claims which follow.

What is claimed is as follows:

1. A device of the character described comprising, in combination, a work-piece supporting base; a pressure exerting member adapted to engage the work-piece; means normally directly engageable by said member for limiting its movement toward the work-piece; and means adapted to render said means unengageable by the pressure exerting member in response to a predetermined pressure upon the supporting base.
2. A device of the character described comprising, in combination, a pressure member; a work-piece supporting base; means for positively limiting the movement of said pressure member; and means for rendering said aforementioned means ineffective when the pressure of said member attains a predetermined value during said limited movement.

3. A device of the character described comprising, in combination, a pressure ram; a work-piece supporting base movable by the ram at a predetermined pressure only; means normally in the path of the ram for positively impeding its progress after it has moved through an initial portion of its travel; and means for moving said aforementioned means out of the path of the ram in response to movement of the base. 80

4. A device of the character described comprising, in combination, a pressure ram; a base for supporting the work-piece, said base being movable by the ram at a predetermined pressure; a detent normally in the path of the ram and adapted to be engaged by the ram positively to stop its movement after it has traveled through an initial portion of its range of movement; means for moving the detent out of the path of the ram; and a body of fluid forced against said last mentioned means to operate it in response to movement of the base. 85 90 95

5. A device of the character described comprising, in combination, a pressure ram; a base for supporting the work-piece; a detent adapted positively to be engaged by the ram and stop its movement after it has traveled through an initial portion of its range of movement, and means responsive to a predetermined pressure by the ram during its said initial movement to render the detent ineffective to stop the ram. 100 105

6. A device of the character described comprising, in combination, a pressure ram; a stop member normally adapted positively to impede the movement of the ram after it has traveled through an initial portion of its range of movement; two cylinders, each containing a piston, one providing a work-piece carrier, the other being attached to the stop member; means connecting the pistons to have them move substantially in unison; a spring urging the stop member piston into normal position, said spring being overcome only by a predetermined pressure of the ram upon the base piston, whereby the stop member piston is operated to move the stop member out of the path of movement of the ram. 110 115 120

7. A device of the character described comprising in combination, a base for supporting a work piece; a pressure member adapted to be moved toward said base; means for stopping the movement of the pressure member; and means adapted to render said stopping means ineffective in response to a predetermined pressure exerted by the pressure member against the work-piece on the base. 125

8. A device of the character described comprising, in combination, a base for supporting a work-piece; a pressure member adapted to be moved a predetermined distance toward the base; means for stopping the movement of the pressure member after it has moved through an initial portion of said predetermined distance; and means adapted to render said stopping means ineffective in response to a predetermined pressure exerted by the pressure member against the work-piece on the base. 130 135 140
